UNITED STATES PATENT OFFICE.

MARTIN MEDART, OF BELLEVILLE, ILLINOIS, ASSIGNOR OF ONE-HALF TO
MARTIN V. MEDART, OF ST. LOUIS, MISSOURI.

CURTAIN-FIXTURE.

SPECIFICATION forming part of Letters Patent No. 286,624, dated October 16, 1883.

Application filed July 31, 1883. (No model.)

To all whom it may concern:

Be it known that I, MARTIN MEDART, a citizen of the United States, and a resident of Belleville, in the county of St. Clair and State of Illinois, have invented certain new and useful Improvements in Curtain-Fixtures; and I do hereby declare that the following is a full, clear, and exact description of the invention, reference being had to the accompanying drawings, forming a part of this specification.

My invention relates more especially to that class of curtain-fixtures in which a single actuating-cord is employed to raise and lower the curtain, such cord being wound around a pulley on the curtain-roller in a direction opposite to that in which the curtain winds; and my invention has for its objects to provide a neat, durable, and effective device or locking mechanism to hold such actuating-cord at any desired adjustment, and furnish a ready and rapid means for changing the adjustment of the curtain as required. I attain these objects by the mechanism illustrated in the accompanying drawings, in which—

Figure 1 is a perspective view of a window-curtain to which my improvement is applied; Fig. 2, a detail section of same, and Fig. 3 a detail perspective view.

Referring to the drawings, A represents the curtain winding upon a curtain-roller, B, in the usual manner. At one end of this curtain-roller is arranged a flanged pulley, C, upon which winds the actuating-cord D in an opposite direction to that in which the curtain A winds upon the roller B, so that the unwinding of the one will wind up the other, and vice versa.

My invention consists in the means employed to operate the actuating-cord D and lock it at any desired position, to accomplish which I make use of the following mechanism:

D' is a runner-sleeve moving freely upon a guide rod or bar, E, and having pivot-ears, be-

tween which the eccentric or cam d is pivoted, and the engagement of said cam with the 45 rod or bar E locks the sleeve at the desired position. This engagement is made automatic by connecting the cord D with the outer or long end or arm of the cam d, as shown, while the disengaging motion is accomplished by 50 hand, a turn knob or handle, d', being provided for convenience of operation. A striking advantage of this construction is that the greater the tendency of the curtain to descend the harder will be the grip or lock of the cam 55 upon the bar or rod E. The guide-rod is made adjustable by having its lower end, e, bent at an angle and adapted to enter one of a series of holes, e², in the window-casing, while the upper end is arranged loose in an eye of the 60 projecting stud or post e', which is also provided with a guide-eye, e³, for the actuating-cord D.

Having thus fully described my invention, what I claim, and desire to secure by Letters 65 Patent, is—

1. The combination of the curtain-roller B, pulley C, and actuating-cord D with the guide-rod E and sleeve D', provided with an eccentric or cam d, the longer end of which is connected with the actuating-cord, as described, and for the purpose set forth.

2. In a holding-fixture for curtains, the combination of eccentric or cam d, operating knob or handle d', sleeve D', and guide-rod E, substantially as and for the purpose set forth.

3. In a holding-fixture for curtains, the combination of the rod E, having its lower end bent at an angle, with the casing provided with a series of holes, e², and guide-stud e', as 80 and for the purpose set forth.

MARTIN MEDART.
